UNITED STATES PATENT OFFICE.

RICHARD CLARENDON KAY, OF SOUTH KENSINGTON, LONDON, ENGLAND.

PORTABLE ELECTRIC LAMP.

Application filed May 7, 1923. Serial No. 637,220.

To all whom it may concern:

Be it known that I, RICHARD CLARENDON KAY, a citizen of the United States of America, residing at No. 19 Redcliffe Road, 5 South Kensington, London, England, have invented certain new and useful Improvements in or Connected with Portable Electric Lamps, of which the following is a specification.

10 This invention relates to improvements in or connected with portable electric lamps of the kind mounted in a lamp socket, connected by a universal or other joint to means such as a flexible or elastic clip or band, for 15 attachment to the finger, wrist or head of the person.

According to this invention, the universal joint is interposed between the reflector or the lamp socket or holder and the means for 20 attachment to the person and the said means for attachment is, moreover, suitably so constructed as in some positions of the lamp to complete the electric lamp circuit and in another position or positions, to open or 25 interrupt the said circuit. In order to provide for wear, one member of the universal joint may be made adjustable. By these improved means the lamp can be switched off merely by turning it beyond a pre-determined 30 limit about one of the universal joint pivots.

Or the lamp-holder or socket is carried by a joint part on which are provided conductors connected with the positive and 35 negative terminals of the lamp-holder or socket. These conductors are so disposed as to be capable of being brought into electrical contact with fixed or elastic contacts of 40 socket terminals mounted in a small block secured in another joint part. Thus, the flexible leads from a cell or battery, or other source of current, can be connected to the 45 terminal pins or pillars of a plug device so that connection and disconnection can be readily effected by the simple insertion or withdrawal of the pins or pillars into or from the socket terminals aforesaid. The 50 one joint part is preferably adjustable on the other in such a manner as to enable the conductors to be brought into or out of contact with the contacts of the block aforesaid. Also, the one joint part is preferably formed 55 with a segment concentric with its pivot, the conductors being laid around the periphery of this segment. Thus, the lamp can be tilted through a considerable angle without the

circuit being broken, the conductors rubbing upon the fixed or spring contacts during the pivotal motion which produces the required tilt. The segment can be designed so that 60 the circuit is broken when a pre-determined angle of tilt is exceeded.

And in order that the invention may be readily understood, reference will be made to the accompanying drawings, in which:—

Figure 1 is a sectional side elevation of one construction of portable electric lamp with an elastic ring for engaging a finger of a person.

Figure 2 is a front view thereof.

Figure 3 is a side elevation showing the lamp in position for opening the lamp circuit.

Figure 4 is a detail view in side elevation of a modified construction of part of the universal joint.

Figure 5 is a side elevation of another modification and,

Figure 6 is a similar view showing the lamp in position for opening the lamp circuit.

Figure 7 is a side elevation of another modification.

Figure 8 is a front elevation of same, and

Figure 9 is a sectional side elevation thereof.

In Figures 1 to 3, *a* is a reflector which is integral with a lamp-holder or socket *b*, but the reflector and lamp-holder may be made separately and subsequently connected together if desired. The lamp *c* is screwed or otherwise fixed in the holder, one terminal contact of the lamp making contact with the pin *d'* electrically connected to the terminal *d*, to which a flexible conductor is 90 in turn connected. The other terminal contact of the lamp, namely, the screw-threaded plug part, makes electrical contact with the metal lamp-holder *b*. A T-shaped bracket *e*, which may be made by bending a single 100 piece of sheet metal, has its head or laterally extending portions riveted to the reflector *a*. The stem portion of the bracket *e* is pivotally connected with a member *f* by means of a small pivot bolt *g*. The member *f* consists of a strip bent to form a rectangular figure with the ends bent to form two upward extensions *f'* between which the stem of the bracket *e* is pivotally mounted as aforesaid. The extensions *f'* may be formed with a laterally projecting pointed part *f''* adapted for acting

as a stop to prevent the reflector from being turned beyond the position seen in Figure 3, so that it is impossible for the reflector *a* to be turned into contact with a terminal pillar *h* which is mounted on the member *f* as hereinafter described. The nut on the bolt or screw *g* is tightened so that the member *e* turns friction tightly between the extensions *f'* of the member *f*.

10 The bottom portion of the member *f* is perforated to receive a pivot such as a rivet *j*, Figure 2, by means of which the member *f* is pivotally connected with a bent plate or clip *k* provided with an elastic finger clip *l* or other means of attachment to the person. The pivots *g* and *j*, having their axes perpendicular to one another, constitute pivots of a universal joint enabling the lamp to be directed or adjusted in any 15 direction.

20 The terminal pillar *h*, above referred to, is conveniently secured to a small block *m* of insulating material, this block being fitted with a conducting strip *n* and the terminal pillar *h* being fixed in electrical contact with that strip. The block *m* is secured within the rectangle of the member *f* by means of a transverse bolt *o* passing through the block and through perforations in the side portions of the rectangle, a nut *p* being screwed tightly on to the end of the bolt. The perforations in the said side portions may be elongated holes such as *f'*, which permit of 25 vertical adjustment of the block *m*.

30 In the example seen in Figures 1 to 3, the forward edge of the stem portion of the member *e* is contoured to form an arc of a circle at *e*², this arc being struck from the centre of the pivot *g*. The rearward edge, however, is cut away so as to form a chord which lies within the circle of which the arc at *e*² forms a part. The stem of the member *e* is insulated from the parts *f'* by means of 35 insulating washers indicated at 1. A suitable washer 2 may also be interposed between the parts *f* and *k*.

40 In use, the two wires from a battery or other source of electricity are connected to respective terminals *d* and *h*. The reflector *a* and joint member *e* are turned about the pivot *g* to the position seen in Figure 1, and if the contact strip *n* on the block *m* is not then in contact with the arcuate edge *e*² of the member *e*, the block *m* is adjusted vertically as aforesaid to bring the strip *n* into contact with the arcuate edge *e*². Owing to the said arc being concentric with the pivot *g*, the reflector *a* and member *e* can be turned forwardly through a considerable angle, without the arcuate edge *e*² losing contact with the strip *n*. So long as this contact is preserved, the lamp circuit is completed as follows:—From the battery to the terminal *d*, through the pin *d'* and filament of the lamp to the screw-threaded socket or plug 45

of the lamp, through the screw-threaded lamp-holder *b* and the metal reflector *a* to the joint member *e*, from the latter into the strip *n* and so to the terminal *h*. If the reflector *a* and joint member *e* be turned 75 rightwardly from the position seen in Figure 1 to that shown in Figure 3, the arcuate edge *e*² loses contact with the strip *n* and the lamp circuit is broken. The point at which contact is to be broken as aforesaid, can be predetermined, of course, for any desired angle of tilt about the pivot *g*.

According to the modification illustrated in Figure 4, the block *m* with its metal strip *n* as described with reference to Figures 1 to 3 is replaced by a sleeve *q* of insulating material surrounding the bolt *q'*, a conductor ring *r* being fixed around the sleeve *q* as shown. A terminal pillar *s* is formed in one with or attached to the ring *r* and takes the place of the terminal pillar *h* of Figures 1 to 3. The operation of this modified construction is exactly the same as described with reference to Figures 1 to 3, excepting that the contoured edge of the member *e* makes contact 85 with the ring *r* instead of with a flat strip.

The modification illustrated in Figures 5 and 6 is adapted for breaking the lamp circuit when the reflector *a* and member *e* are turned forwardly or in the direction in which the light is projected. The construction is very similar to that seen in Figures 1 to 3, but the concentric arcuate edge indicated at *e*³ on the rearward edge of the member *e* extends around a greater angle than the arc *e*² in Figures 1 to 3 and merges into a curve of decreasing radius on the forward edge of the member *e*. By comparing Figure 6 with Figure 5, it will be seen that the lamp circuit is broken by turning the reflector and member *e* forwardly about the pivot *g*. On the other hand, the reflector *a* can be turned rearwardly or rightwardly from the position seen in Figure 5, through a considerable angle without the edge *e*³ losing 95 contact with the strip *n*. Figures 5 and 6 show the pivot *j* connecting the member *f* with a metal strip *t* secured by rivets or any other suitable means to a wrist or head strap *u* instead of to a finger clip, as will be readily 100 understood.

According to the construction shown in Figures 7, 8 and 9, the lamp socket or holder *b* (which may be integral with the reflector *a* or attached to the latter by screwing) is screwed into one end of a flat piece *e*⁴ of insulating material, such as wood or ebonite. The bore of the lamp-holder or socket is transverse to the length of the flat piece *e*⁴. The opposite end portion of this piece *e*⁴ is formed on one side with a segmental periphery *e*⁵ extending around, say, somewhat more than 90°, and on the other side with a longitudinal straight edge *e*⁶. The segmental periphery *e*⁵ is concentric with a pivot hole 110 115 120 125 130

drilled through the said end portion. In the side of the piece e^4 of insulating material, formed with the internally screw-threaded socket, two small holes are drilled 5 in suitable positions for lamp terminal contacts. Two strips of copper forming conductors and marked v and v' respectively, each having one end inserted into a respective hole are laid flat against the periphery of 10 the segmental portion of the flat piece and so as to extend from the neighbourhood of the lamp socket down and around the segmental portion and up the straight edge portion where their opposite ends are embedded 15 in the piece e^4 of insulating material or secured by small screws or the like. A wrist strap u , or a finger ring or the like is fitted with a pivot j , on which is mounted a member, bracket or clamp f^4 made of a strip of 20 sheet metal, bent to form a rectangular figure with the ends bent to form two upward extensions f^5 . The limbs of the member or clamp are suitably bent to form recesses and a small rectangular block m' of insulating 25 material is inserted into the member or clamp f^4 . The said block m' is formed with two transverse parallel bores into which are inserted fixed terminals such as the sockets $d' h'$. On that surface of the 30 block which is presented upwardly between the limbs $f^5 f^5$, two spring contact studs d^2 and h^2 are fitted in electrical connection with respective sockets $d' h'$. The limbs $f^5 f^5$ of the member or clamp f^4 are 35 formed with holes f^6 , and the flat piece aforesaid is inserted between the limbs so that its pivot hole comes fair with the holes f^6 . A screw-threaded pivot pin or bolt g is then inserted through the holes and pivot 40 holes in flat piece e^4 and is secured by a nut and washer. If spring contacts d^2 and h^2 are employed, these allow of the assembling of the parts without any adjustment between the part e^4 and the block m' , 45 but if fixed contacts be used, the holes in the limbs f^5 must be in the form of oblong slots, and then by adjusting the pivot g of the flat piece down the slots in the limbs f^5 towards the block m' , the conductor strips v 50 v' on its periphery may be brought into contact with the contact studs of the block, whereupon the nut is tightened and the flat piece is held friction-tight in the clamp. The conductors of a double flex are connected 55 on the one hand to respective pins or pillars $w w'$ on a plug or bridge piece w^2 and on the other hand with poles or terminals of a source of electricity. The pins or pillars $w w'$ are then inserted into the sockets of the small terminal block m' , whereupon the 60 circuit of the lamp is completed. The clamp f^4 may be turned around its pivot j in one plane, and the flat piece e^4 can be turned about its pivot in a plane perpendicular to the plane in which the clamp f^4 is turned. 65

So long as the flat piece e^4 is turned with the conductors $v v'$ on its segmental periphery in contact with the spring contacts $d^2 h^2$, mounted in the block, the circuit is maintained, but if it should be turned beyond a certain point, the conductors $v v'$ pass out of or lose contact and the lamp circuit is broken. 70

I claim:—

1. In a portable electric lamp, the combination of a lamp holder, means for attaching said holder to a person, terminals for connection with a supply of electricity, a universal joint connection between said lamp holder and attaching means, one member of the universal joint acting as a sliding electric contact during a relatively large angular movement of said member about its pivot, and acting as a cut off switch during further movement, substantially as set forth. 75

2. In a portable electric lamp, the combination of a lamp holder and attaching means for said holder, terminals for connection to a supply of electricity, a universal joint connection between said lamp holder and the attaching means a plane electrical contact on one joint member, and an eccentric surface on another member of the universal joint adapted to contact with said plane electrical contact during a certain arcuate 90 movement of said member and to be out of contact on further movement, substantially as set forth. 95

3. In a portable electric lamp, the combination of a lamp holder, attachment means therefor, a universal joint connection between said lamp holder and attachment means, a plane portion on one joint part of said universal joint, an electrical contact on said plane portion, a peripheral segmental portion on the other joint part, an electrical contact on said segmental portion adapted to make contact with the electrical contact on the plane portion according to the position of the said segmental portion 100 in relation to the plane portion, a terminal adapted to be electrically connected with one of the lamp terminals through the universal joint and another terminal adapted to be electrically connected with the other 105 lamp terminal, substantially as set forth. 110

4. In a portable electric lamp, the combination of means for attaching it to the person, a universal joint, a lamp-holder, the said universal joint comprising a pivot mounted on the said means of attachment, a frame mounted on the said pivot having a base and two parallel members, an electric contact mounted in the said frame perpendicular to the pivot, a pivot pin mounted in the said frame remote from the contact and perpendicular to the pivot aforesaid, a segmental portion mounted on the pivot pin so as to be partially rotatable thereon and in one position to be out of contact with the 115 120 125 130

contact in the frame and in other positions contacting therewith, mounted on the said segmental portion and terminals, one of the said terminals being adapted to be in electric connection with one of the lamp terminals through the universal joint and the other terminal adapted to be in electric connection with the other lamp terminal, substantially as set forth.

- 10 5. In a portable electric lamp, the combination of means for attaching it to the person, a universal joint constituted by a pivot, mounted on the said attachment means, a frame, mounted on the said pivot, having a base and two parallel members, a block of insulating material at the base of the frame, a pair of terminals fixedly mounted in the said block, an electric contact projecting from each terminal, a pivot pin mounted in the said frame remote from the contacts and perpendicular to the pivot aforesaid, a joint member of insulating material having a segmental portion at one end and a screw-threaded socket at the other end, the said joint member being mounted on the pivot pin so as to be partially rotatable thereon, an electric lamp holder adapted to be screwed into the said socket, a pair of conductors mounted on the segmental portion, one conductor extending into the screw-threaded socket to make contact with one lamp terminal and the other conductor extending into another part of the screw-threaded socket to make contact with the other lamp terminal, a reflector and lamp holder adapted to be screwed into the said screw-threaded socket, substantially as set forth.

6. In a portable electric lamp, the combination of means for attaching it to the person, a universal joint constituted by a pivot mounted on the said attachment means, a rectangular frame, mounted on the said pivot, having a base and two parallel members, a block of insulating material, partially enclosed and fixed in the said base of the frame, a pair of terminals fixedly mounted in the said block, an elastically mounted electric contact projecting from each terminal, a pivot pin mounted in the said frame remote from the contacts and perpendicular to the pivot aforesaid, a joint member of insulating material having a segmental portion at one end and a screw-threaded socket at the other end, the said joint member being mounted on the pivot pin so as to be partially rotatable thereon, an electric lamp holder adapted to be screwed into the said socket, a pair of conductors mounted on the segmental portion, one conductor extending into the screw-threaded socket to make contact with one lamp terminal and the other conductor extending into another part of the screw-threaded socket to make contact with the other lamp terminal, a reflector and lamp holder adapted to be screwed into the said screw-threaded socket, substantially as set forth.

RICHARD CLARENDRON KAY.
